UNITED STATES PATENT OFFICE

WALTER H. PARKER, OF BEAVER, PENNSYLVANIA, ASSIGNOR, BY MESNE ASSIGNMENTS, TO THE WAYNE PUMP COMPANY, OF BALTIMORE, MARYLAND, A CORPORATION OF MARYLAND

LIQUID-DISPENSING APPARATUS

Application filed July 13, 1925. Serial No. 43,152.

This invention relates to liquid dispensing apparatus.

One object of the invention is to provide simple, reliable and efficient means for automatically draining the measuring container when the casing door of the apparatus is closed, as for example, when the use of the apparatus is discontinued for the night.

Another object is to provide a draining arrangement for liquid dispensing apparatus in which the parts cooperate in a manner to meet all requirements.

These and other objects are accomplished by means of the arrangement disclosed on the accompanying sheet of drawings in which Fig. 1 is a vertical longitudinal sectional view of liquid dispensing apparatus, embodying my invention; and

Fig. 2 is an enlarged detail sectional view of a part of the apparatus and disclosing the invention.

Fig. 3 is an enlarged fragmentary sectional elevation through the drain control valve.

The various novel features of the invention will be apparent from the following description and drawings and will be particularly pointed out in the appended claims.

Referring to the figures of the drawings, it will be noted that the invention is illustrated in connection with liquid dispensing apparatus including transparent measuring container 10 mounted between a base plate 11 and a cover 12. A casing 13 which supports the measuring container, in turn is supported by a base 14. Mounted within the base 14 is a pump 15 for pumping liquids, such as gasoline, from any suitable source represented by reference character 16 up through a supply pipe 17 which terminates in the U-shaped portion 18 within the container 10. An overflow pipe 19 extending up into the container 10 determines the maximum height of the liquid within said container. A vertically adjustable discharge conduit 20 also extends into the measuring container 10 and below the latter is provided with an operating handle 21 whereby the discharge conduit 20 may be raised, lowered and rotated. The discharge conduit may be locked in va-

rious adjusted positions by moving the handle 21 laterally into the recesses of any one of a number of spaced locking members 22 mounted upon any suitable support 23 which in this instance, is a drain pipe to be referred to hereinafter.

The top of the discharge conduit 20 is provided with any suitable valve mechanism 24 whereby normally liquid is prevented from discharging from the measuring container 10 through the discharge tube 20. The valve of this valve mechanism however, may be opened through suitable mechanism when the handle 21 is moved laterally into the recess of any of the locking members 22 for permitting discharge of liquid from the container 10 through said discharge conduit 20. The valve mechanism in question forms no part of the invention and accordingly, further description of same will not be given. The discharge conduit 20 is telescopically arranged with respect to one leg 24 of a well 25, the other leg 26 of which terminates in an outlet pipe 27 to which a service or discharge hose 28 is connected.

In connection with the operation of the device thus far described, it will be appreciated that if the top of the discharge conduit 20 is lowered below the level of the liquid in the measuring container 10 and the handle 21 is moved into engagement with one of the locking members 22 that liquid will be discharged from said container through the discharge conduit, well 25, pipe 27 and hose 28. A vent pipe 29 extends from the upper end of the well leg 26 for preventing siphoning of the liquid from said well.

The drain pipe 23 referred to hereinabove extends through the base plate 11 and communicates with the interior of the measuring container 10. The drain pipe 23 is connected at 30 to the overflow pipe 19 so that liquid drained from the measuring container passes through the drain pipe 23 and then through the overflow pipe 19 back to the source of supply. Normally draining action is prevented by a valve 31 having a stem 32. As shown in Fig. 1, the valve stem 32 extends out of the valve casing and the valve, under the pressure of the usual spring, is releasably held

in closed position. As shown in Figure 2, the valve stem is pressed inwardly by a trigger 33 for opening the valve with the result that the measuring container is drained. Referring more specifically to the valve shown in Figure 3, it will be seen that the valve 31 is connected to the parts of the drain pipe 23 and is provided with the valve stem 32 operated by one arm 50 of the trigger 33, the trigger being pivotally supported as at 51 to the bracket 52 provided on the valve 31. The valve stem is provided with the valve disc 53 seated on the valve seat 54 and spring pressed by spring 55 to maintain the valve disc in normally seated position, preventing draining through the pipe 23. Secured to the outer end 56 of the trigger at the point 34 is a valve operating member 35, the upper end of which is provided with a lip 36 which as shown in Fig. 2 is engaged and raised by a flange 37 on the lower edge of the door 38 of the casing 13. In other words, when the door 38 is raised for completely enclosing the control mechanism of the pump, the lower flange 37 of the door 38 passes into engagement with the lip 36 of the operating member 35 and raises the latter for opening the drain valve, whereupon liquid is permitted to drain from the measuring container 10. When however, the door 38 is lowered, the valve automatically and immediately closes through action of the spring 55, the upper end of the valve operating member 35 being enclosed or encased by a pocket portion 39 formed at the upper end of the door. This pocket prevents meddling with said member and also improper operation of said valve when the door is open. By thus housing the upper portion of the valve operating member 35, protective means is provided whereby the purchaser of liquid is more apt to secure the full amount of liquid purchased.

I claim:

1. In liquid dispensing apparatus, the combination of a casing for control parts of the apparatus, a measuring container, means for controlling the draining of said container including a self-closing valve and a valve operating member, said valve having means therein for positively closing said valve, said casing having a door with a portion for operating said member and valve to drain said container when the door is moved into one position and having another portion for embracing said member to prevent meddling with said member and improper operation of said valve when the door is in another position.

2. In liquid dispensing apparatus, the combination of a casing for control parts of the apparatus, a measuring container, a drain pipe therefor, an automatically closed valve in said drain pipe, and a valve operating member, said valve having means therein for positively closing said valve, said casing hav-

ing a door with a portion for operating said member and valve to drain said container when the door is moved into closed position and having another portion for embracing said member to prevent meddling with said member and improper operation of said valve when the door is open.

3. In liquid dispensing apparatus, the combination of a casing having a closure, a container associated with said casing for receiving liquid, a drain therefrom, said drain having a spring loaded valve normally maintaining said valve in closed position whereby said drain is inoperative, means between said closure and valve for opening said valve to drain position, and means on said closure for preventing operation of said valve in a different position of said closure.

4. In liquid dispensing apparatus, the combination of a measuring container, a supporting casing therefor, discharge means from said container, operating and measuring means for said discharge means controlled from a point inside said casing, a drain connected to said container and disposed in said casing, a vertically sliding door in said casing permitting and preventing access into said casing, a normally closed valve disposed in said drain having a spring pressed closure member operable to open position to cause draining of said container, means for operating said closure member, means on one edge of said door located inwardly of said casing for operating said last named means to open position when said door is closed, and means on another edge of said door located inwardly of said casing for preventing operation of said means for operating said closure member when the door is opened.

Signed at Rochester, Pa., this 6th day of July, 1925.

WALTER H. PARKER.
